US00D952884S

(12) **United States Design Patent** (10) **Patent No.:** **US D952,884 S**
(45) **Date of Patent:** **** May 24, 2022**

(54) **MASSAGE GUN**

(71) Applicant: **XIAMEN SIMO ELECTRONIC CO., LTD**, Fujian (CN)

(72) Inventor: **Jeson Wang**, Fujian (CN)

(73) Assignee: **XIAMEN SIMO ELECTRONIC CO., LTD**, Fujian (CN)

(**) Term: **15 Years**

(21) Appl. No.: **29/729,496**

(22) Filed: **Mar. 27, 2020**

(30) **Foreign Application Priority Data**

Sep. 30, 2019 (CN) 201930540531.3

(51) **LOC (13) Cl.** **28-03**

(52) **U.S. Cl.** ..... **USPC D24/215**

(58) **Field of Classification Search**

USPC D24/200, 211, 212, 213, 214, 215;
D8/14.1; D28/13

CPC . A61H 2201/1635; A61H 23/006; A61H 1/00

(57) **CLAIM**

The ornamental design for a massage gun, as shown and described.

DESCRIPTION

FIG. 1 is a perspective view of a massage gun showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The white evenly spaced broken lines in the drawings represent portions of the massage gun that form no part of the claimed design. The black uneven dot-dash broken lines in the drawings represent a boundary line that form no part of the claimed design. The lighter shaded portions of the massage gun shown within the black uneven dot-dash boundary lines form no part of the claim design.

1 Claim, 8 Drawing Sheets
